RAKE HEAD

Woodrow E. Vaughan and Gerald D. Reed, Independence,
Mo., assignors to Modern Plastic Sales, Independence,
Mo.

Filed Oct. 5, 1970, Ser. No. 25,327

Term of patent 14 years

Int. Cl. D8—01

U.S. Cl. D8—13

FIG. 1 is a top plan view of a rake head;
FIG. 2 is a side elevational view;
FIG. 3 is a fragmentary end view;
FIG. 4 is an enlarged, fragmentary, bottom view;
FIG. 5 is a fragmentary, cross-sectional view taken on line 5—5 of FIG. 4;
FIG. 6 is an enlarged cross-sectional view taken on line 6—6 of FIG. 1; and
FIG. 7 is an enlarged cross-sectional view taken on line 7—7 of FIG. 1.

We claim:
The ornamental design for a rake head, as shown.
